UNITED STATES PATENT OFFICE.

GUSTAVUS CHRISTIAN KIRSCHMANN, OF NEW YORK, N. Y.

IMPROVEMENT IN ARTIFICIAL LIMBS.

Specification forming part of Letters Patent No. 43,031, dated June 7, 1864.

To all whom it may concern:

Be it known that I, GUSTAVUS CHR. KIRSCHMANN, of the city, county, and State of New York, have invented a new and useful Improvement in Artificial Limbs; and I do hereby declare that the following is a full, clear, and exact description of the same, reference being had to the accompanying drawings, forming a part of this specification, in which—

Figure 1 represents a longitudinal vertical section of an artificial leg constructed according to my invention, the line $x x$, Fig. 2, indicating the plane of section. Fig. 2 is a rear elevation of the same. Fig. 3 is a plan or top view of the foot detached. Fig. 4 is a detached side elevation of the knee-joint when bent. Figs. 5, 6, and 7 are detached sections of different toes. Fig. 8 is a detached side elevation of the fulcrum pin of the knee-joint.

Similar letters of reference in all the figures indicate corresponding parts.

The principal object of this invention is to combine with the various joints, or with the springs which control the motion of said joints, certain cords or straps in such a manner that by pulling such cords or straps the position of the joints can be adjusted or the tension of the springs regulated to suit different circumstances.

The invention consists, also, in the employment or use of an oval or eccentric pin in the knee-joint in such a manner that by turning said pin the length of the leg may be slightly altered, either lengthened or shortened, as may be desirable; further, in the application of an adjustable screw, in combination with the spring in the ankle-joint, in such a manner that the extent of the motion of the ankle-joint can be regulated, and that in bending the leg forward the screw, by coming in contact with said spring, relieves the leg from the sudden strain to which it would be exposed if its motion should be stopped suddenly.

To enable those skilled in the art to make and use my invention, I will proceed to describe it.

A represents an artificial leg, the shell of which is struck up of sheet-brass or other suitable material in the proper form or shape to imitate a natural leg. It is made in two parts, which unite at the knee-joint, and the knee is represented by a globe-shaped projection, A,

which enables the two parts to work easy and with little friction. The stump of the amputated limb is inserted into the cup B, which is also made of sheet metal or other suitable material, and perforated with a large number of holes to provide for ventilation. This cup connects by a rod, a, with the knee-joint C, and the rod a is provided with a screw-thread and nut b, so that the distance between the knee-joint and cup can be adjusted at pleasure. The lower end of the rod a is provided with a fork, a', which has its bearing on the fulcrum-pin c of the knee-joint, and which is situated between a similar fork, d', on the upper end of a rod, d, extending from the knee-joint to the ankle-joint. The fulcrum-pin c of the knee-joint passes through the sides of the shell A, and it is made oval or eccentric, so that by turning it the position of the forks a' and d' in relation to each other is slightly altered, and the length of the leg can be varied to a certain extent to make up for wear or for the purpose of a final adjustment of said length. The rods a and d are surrounded by tubes D and E, which are forked—the tube D at its lower end and the tube E at its upper end—and the forks thus formed have their bearings on the fulcrum-pin c of the knee-joint, and said tubes serve to strengthen the leg and to steady the knee-joint. The lower tube, E, is provided with two pairs of arms, e and e', one pair, e, being secured to the upper end of said tube, and the other pair, e', at a short distance below. These arms form the bearings for a series of friction-rollers, f, which form the guides for the various ropes by which the springs of the several joints can be strained or the joints set to suit circumstances. From the centers of the arms e small tubes e* extend to the inside of the shell, and these tubes form guides for the fulcrum-pin c of the knee-joint. Similar tubes, e*, (see Fig. 4,) are secured to the arms e', for the purpose of connecting the shell with the internal mechanism of the leg.

F F' are two sleeves, one sliding on the tube D and the other on the tube E. The sleeve F, which slides on the tube D, is supported by a shoulder, g, and the sleeve F', on the tube E, bears against the arms e', as clearly shown in Figs. 1 and 4 of the drawings, and each of the sleeves is provided with arms f* f'', which form the bearings for the axles of

friction-rollers h h^* h' h'' . Said arms and sleeves are connected by springs G G' , of india-rubber or other suitable material, the springs G being secured to the friction-rollers h h' , and the springs G' to loops i i' , which are attached to the outer surfaces of the arms f^* and f''^* , as shown in Fig. 4. These springs govern the motion of the knee-joint, and their tension is regulated by ropes H H' . The rope H is secured to the roller h^* on the sleeve F , and the rope H' to the roller h''^* on the sleeve F' . The rope H extends in a direct line up between the shell and cup, and connects with the body-strap, and the rope H' extends from the roller h''^* down over a roller, i^* , in the end of two arms, i^* , that are firmly secured to the tube E below the sleeve F' , and from this roller it (the rope) extends up between a set of guide-rollers between the arms e and through between the shell and cup; and it is also connected to the body-strap the same as the rope H . By pulling the rope H' the sleeve F' is drawn down, and consequently the distance between the two sleeves; and with it the tension of the springs G G' , are increased. By tightening or slackening the ropes H H' , therefore, the tension of the springs can be regulated at pleasure. In bending the knee-joint the springs G bear against the friction-rollers f in the ends of the arms e , and the springs G' against friction-rollers e^* , which rotate on the outside of the forks at the ends of the tubes D F on the fulcrum-pin c of the knee-joint. By these rollers the springs are protected against injury. The motion of the knee-joint is further facilitated and softened by a metal spring, a^* , attached to the inside of the shell A , and bearing against the rubber spring G . The tube F terminates below in a disk, E^* , which forms the support for the bearings of friction-rollers e^* e^{**} , to guide the adjusting-ropes of the ankle-joint and of the toe joint or joints, and which is provided with flanges i^2 , whereby the lower part of the shell can be conveniently fastened to the tube E . The ankle-joint I has its fulcrum on a pivot, i^* , which has its bearings in two flanges, i^2 , rising from a standard, I^* , which is secured in the shell A^* of the foot, and said pivot also passes through a fork, d^4 , secured to the lower end of the screw rod d , as clearly shown in Fig. 1. The motion of the ankle-joint is governed by a spring, J , which is secured on the inside of the shell A^* , and the loose end of which bears against the fork d^* at the bottom end of the rod d . A set-screw, j , which is inserted in the fork and bears on the spring J , serves to regulate the tension of said spring and reduce the jar in bending the ankle forward. The toe part K may either be made by combining all the toes in one shell and exposing the same to the action of the spring J^* , assisted by the spring-sole K' ; or each toe may be represented separately and provided with a separate spring, as shown in Figs. 5, 6, and 7. The toe part or toes are

entirely disconnected from the shell A^* of the foot, and they are fastened down upon the sole a^4 by means of solder or by screws, or in any other desirable manner. The spring sole K' is made of a thin plate of sheet-steel, and it is secured to the sole a^4 by means of screws, or in any other suitable manner. The toe part K is so attached to the sole a^4 that a gap, k , is left between its inner edge and the edge of the shell A^* , and this gap is filled out by a strip, l , of india-rubber or other suitable elastic material, whereby the toe part is held in the natural position when the foot is at rest or set down upon a flat surface. The position of the toe part K is regulated by two ropes, L L' , which are attached to a roller, m , having its bearing s in suitable standards in the front end of said toe part. The rope L extends from the roller m over a roller, n , which is secured to the fork d^4 at the lower end of the rod d , and thence up through between the guide-rollers e^2 on the disk E^* , and its upper end is hooked onto the roller h on the sleeve F . If the sleeve F is drawn up by the action of the rope H , a strain is exerted on the rope L , and simultaneously with increasing the tension of the springs of the knee-joint the toe-joint is also strained and set to correspond to the increased tension of the knee-joint. The rope L may, however, be continued up and connected to the body-strap, so that it can be strained independently of the springs of the knee-joint. The rope L' extends from the roller m over a roller, n' , at the back end of the standard I^* , which supports the ankle-joint, and thence it extends up and through between guide-valves e^{**} on the disk E^* , and through between the rollers f on the arms e and f''^* on the sleeves, and its upper end passes out between the cup and shell and connects to the body strap. By pulling this rope the toe part can be adjusted independent of the knee joint. The ropes L L' may be made of some elastic material, so that they act as springs and also as regulators. The motion of the various ropes between the cup and shell is facilitated by friction-rollers a^5 , attached to the sides of the cup. In case the toes K^* are represented separately, as shown in Fig. 3, and detached in Figs. 5, 6, and 7, each toe is fastened to the sole-plate a , leaving a gap between its inner edge and the edge of the shell A^* , and the ropes L L' are connected to a cross-bar, l' , which connects the links l of the several toes. (See Fig. 5.)

The joints of the toes may be produced in different ways, either in the manner shown in Fig. 5 or as represented in Figs. 6 or 7, and the same joints may be applied to artificial fingers, and said toes may be secured by means of screws, or in any other desirable manner.

It remains to remark that the joint which I have here described as the knee-joint and the manner of regulating the tension of the springs may be applied with equal advantage

to artificial arms, said joint being made to represent the elbow-joint.

What I claim as new, and desire to secure by Letters Patent, is—

1. The globe-shaped projection A', uniting the two parts of the shell A, as and for the purpose shown and described.

2. The oval or eccentric fulcrum-pin c of the knee-joint, as and for the purpose described.

3. The combination of the tubes D and E with the screw-rods a and d and shell A, as and for the purpose set forth.

4. The small tubes e* e', in combination with the tube E, rod d, and shell A, as and for the purpose specified.

5. The arms e e', provided with guide-rollers f, in combination with the tube E and ropes H H' L L', as and for the purpose described.

6. The sleeves F F', in combination with the springs G G', tubes D E, and rods a d, as and for the purpose set forth.

7. The ropes H H', in combination with the sleeves F F' and springs G G', constructed and operating substantially as and for the purpose shown and described.

8. The spring a*, attached to the shell A, in combination with the spring G of the knee-joint, as set forth.

9. The disk provided with flanges c', in combination with the tube E and shell A, as and for the purpose specified.

10. The set screw j, in combination with the springs J J* and ankle-joint I, constructed and operating substantially as and for the purpose set forth.

11. The rope L, in combination with the toe-piece K, sleeve F, rope H, and springs G G', all constructed and operating substantially as and for the purpose described.

12. The rope L', in combination with the spring-sole K' and toe-piece K, as and for the purpose specified.

13. The cross-bar l', in combination with the toes K* and ropes L' L', constructed and operating as and for the purpose specified.

GUSTAVUS CHRISTIAN KIRSCHMANN.
